(57) **CLAIM**

I claim the ornamental design for a soundbar, as shown and described.

DESCRIPTION

FIG. 1 is a front perspective view of the soundbar;
FIG. 2 is a front-on view of the soundbar;
FIG. 3 shows a rear view of the soundbar;
FIG. 4 shows a first side-on view of the soundbar;
FIG. 5 shows a second side-on view of the soundbar;
FIG. 6 shows a top view of the soundbar; and,
FIG. 7 shows a bottom view of the soundbar.
The broken lines shown are included for the purpose of illustrating portions of the soundbar that form no part of the claim.

1 Claim, 4 Drawing Sheets
